(57) **CLAIM**

The ornamental design of a tube for pulling rod, as shown and described.

DESCRIPTION

FIG. 1 is a perspective view of a tube for pulling rod showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the tube relative to the body of a pulling rod. The broken lines showing a portion of the adjacent tube, luggage handle and handle insert are for the purposes of illustrating environment and form no part of the claimed design.
